MILITARY SERVICE RIBBON ATTACHMENT

Arthur E. Du Bois, Washington, D. C., assignor
to the United States of America as represented
by the Secretary of the Army

Application September 29, 1952, Serial No. 21,648

Term of patent 14 years

(Cl. D29—2)

To all whom it may concern:

The invention described herein, if patented, may be manufactured and used by or for the Government for governmental purposes, without the payment to me of any royalty thereon.

Be it known that I, Arthur E. Du Bois, a citizen of the United States and resident of the city of Washington, in the District of Columbia, have invented a new, original, and ornamental Design for a Military Service Ribbon Attachment, of which the following is a specification, reference being had to the accompanying drawings, forming a part thereof.

Figure 1 is a front elevational view of a military service ribbon attachment, showing my new design.

Figure 2 is a front perspective view of the same on an enlarged scale, and

Figure 3 is a rear perspective view of the same.

The dotted line disclosure of a service ribbon in Figure 1 is for purposes of illustration only.

The essential features of my design are shown in full lines.

I claim:

The ornamental design for a military service ribbon attachment, as shown and described.

ARTHUR E. DU BOIS.
